(57) **CLAIM**

The ornamental design of a T-handle hex wrench, substantially as shown and described.

DESCRIPTION

FIG. 1 is a perspective view of a T-handle hex wrench embodying the design of the present invention;

FIG. 2 is a front elevation view of the T-handle hex wrench illustrated in FIG. 1;

FIG. 3 is a back elevation view of the T-handle hex wrench shown in FIG. 1;

FIG. 4 is a left side view of the T-handle hex wrench shown in FIG. 1;

FIG. 5 is a right side view of the T-handle hex wrench shown in FIG. 1;

FIG. 6 is a top view of the T-handle hex wrench illustrated in FIG. 1; and,

FIG. 7 is a bottom view of the T-handle hex wrench illustrated in FIG. 1.
